UNITED STATES PATENT OFFICE

2,532,812

CHAIR AND TRAY COMBINATION

John E. Huber, Cincinnati, Ohio

Application September 3, 1946, Serial No. 694,497

7 Claims. (Cl. 155—128)

1

This invention relates to chairs and more especially to children's or infant's chairs of a type which may be folded or collapsed for purposes of portability.

The invention embraces the provision of a chair in which the seat and back portions are relatively movable for purposes of collapsibility and the seat supporting means arranged to be quickly and readily detached to render the structure portable and one which may be encompassed in a small space.

An object of the invention is the provision of a chair construction particularly adapted for infant's use which may be folded or collapsed to enhance the transportation of the chair especially for travel purposes.

Another object of the invention resides in the provision of an infant's chair in which the major constituents are fabricated of metal and of such construction as to secure rigidity and strength with a minimum of weight.

Another object of the invention is the provision of a chair especially adapted for infant's use having a tray and tray support arranged to be readily removed and reassembled.

A further object of the invention resides in the construction of an infant's chair having a tray support centrally disposed with respect to the seat portion independently of the chair arms and in which the tray may be adjusted relative to the support.

A further object of the invention is the provision of an infant's chair equipped with a foot rest mounted for adjustment in several different positions with respect to the seat portion in which adjustment is obtained without the manipulation of any securing members or the like.

A further object is the provision of a chair in which side arms are journaled for swinging movement upon means associated with the seat back and arms, the arms being removably connected to the seat portion by simple, yet effective, attachment means arranged to secure a rigid connection.

Still a further object of the invention resides in the provision of supporting legs for a chair which may be fabricated of thin walled tubing and in which reinforcing means are utilized at the points of securing the legs to the seat portion providing an exceptionally rigid connection yet one in which the legs may be quickly and easily removed from the seat.

Further objects and advantages are within the scope of this invention such as relate to the arrangement, operation and function of the related

2

elements of the structure, to various details of construction and to combinations of parts, elements per se, and to economies of manufacture and numerous other features as will be apparent from a consideration of the specification and drawing of a form of the invention, which may be preferred, in which:

Figure 1 is a front perspective view illustrating an embodiment of the chair of my invention;

10 Figure 2 is a top plan view of the seat portion of the chair;

Figure 3 is a vertical sectional view taken substantially on the line 3—3 of Figure 2;

15 Figure 4 is a fragmentary detail view illustrating the foot rest in one position of adjustment;

Figure 5 is a fragmentary detail sectional view of the means connecting the tray support with the seat;

20 Figure 6 is a side elevational view of the seat and back portions of the chair, certain parts being shown in section;

Figure 7 is a perspective view illustrating a collapsed position of the seat back and side arm construction;

25 Figure 8 is a detail sectional view taken substantially on the line 8—8 of Figure 6;

Figure 9 is a fragmentary detail sectional view taken substantially on the line 9—9 of Figure 6;

30 Figure 10 is a fragmentary detail sectional view taken substantially on the line 10—10 of Figure 6;

Figure 11 is vertical sectional view through the feeding tray and supporting construction;

35 Figure 12 is a detail sectional view taken substantially on the line 12—12 of Figure 11, and

Figure 13 is a detail sectional view taken substantially on the line 13—13 of Figure 2.

While I have illustrated a form of my invention as embodied in an infant's or children's chair, it is to be understood that I contemplate the application of the principles of my invention to any construction or article forming an occupant's support.

Referring to the drawings in detail, the chair 45 construction illustrated is inclusive of a seat or seat portion 10, a back portion 11, side arms 14 and 15, a foot rest 16 and a tray 17. The seat 10 is provided with a uniplanar seating surface 20 which is of substantially rectangular contour and is bounded by a depending peripheral skirt portion 21. The seat is supported upon pairs of legs or supports 23 and 24. Each of the supporting legs is secured to the seat by independent means so that each support may be disengaged 50 from the seat. In the illustrated embodiment,

each leg or support is fabricated of thin-walled metal tubing, as for example aluminum or thin gauge steel, to reduce the weight to a minimum. In order to provide a substantial area for the point of engagement of the tubes with the floor or other supporting surface the lower extremities of the tube may be provided with plugs 25 placed into the lower end of each tube. The lower surface of the plugs 25 are preferably slightly convex to prevent damage to the linoleum or floor surface.

The upper ends of the tubes are secured to the skirt portion of the seat through means rendering the tubes readily removable. As illustrated particularly in Figure 13, the upper extremity of each of the tubes is formed with a longitudinally extending open ended slot 27 which accommodates a bolt 28. The bolt 28 is provided with a knurled portion 29 which is pressed into an opening formed in a corner of the skirt portion 21. When thin-walled tubing is utilized for the supports 23 and 24 it is preferable to employ a reinforcing member 30 as shown in Figures 10 and 13, of a diameter to slidably receive the upper extremity of the supporting tube. The reinforcing member 30 is provided with a transversely extending opening through which the bolt 28 extends. The upper end of each reinforcement 30 is formed with a head or shank 32 which serves as a means for determining the position of each supporting leg. A trough-shaped member 33 is adapted to engage the exterior periphery of the upper extremity of a tube or supporting leg to maintain each leg in a rigid position in engagement with the skirt portion 21. As particularly illustrated in Figure 10, the member 33 is preferably shaped to engage the exterior wall of the supporting leg in dual line contact indicated at 34 and 35, this type of engagement serving to align the member 33 and supporting leg properly with respect to the skirt 21 of the seat 10. The end portion of the bolt 28 is threaded to receive a clamping means in the form of a wing nut 36.

In the illustrated embodiment, particularly as shown in Figures 3 and 6, the forward portion of the skirt 21 is of a greater width than the rear portion. By this construction the pairs of legs 23 and 24 may be made of identical lengths but the upper extremities of the legs 23 are spaced farther from the upper surface of the seat 10 than the upper ends of the legs 24, which arrangement provides for a rearward and downward tilt to the seat portion 10. This slanting of the seat not only facilitates the comfort of the occupant but tends to keep the occupant on the seat. As particularly shown in Figures 1, 6 and 7, the skirt 21 of the seat portion is flared outwardly at an angle so that the lower extremities of the supporting legs 23 and 24 engage the floor or other supporting surface at widely shaped points to enhance the stability of the chair construction.

The chair construction of my invention includes a back panel 39 which may be formed of metal, fiber, plastic or the like. The panel 39 is supported by means pivotally connected to the seat portion. To this end, the seat 10 is formed on its lower surface with pairs of spaced depending lugs or bosses 40, each pair being bored with aligned openings to receive pivot pins or pintles 41. Disposed between the lugs of each pair is a member 44 provided with an opening at one extremity to receive the pin 41. As particularly shown in Figure 3, the members 44 are formed

with arcuate portions 45, the curvature of which is generated about the axis of pins 41. The uniplanar portion of the seat 10 is formed with a pair of openings 46 to accommodate the arcuate portion 45 of the hinge members 44. The upper extremities of members 44 project into cylindrical fittings 48 and are secured therein by means of transversely extending pins 49. As will be apparent from an examination of Figure 3, the lower extremities of cylindrical members 48 are provided with head portions 50 which have canted lower surfaces adapted to fit or engage squarely upon the uniplanar upper surface of the seat 10. The head portions 50 of fittings 48 are preferably of a diameter to cover the openings 46 in the seat portion when the seat back is in a position of use as shown in Figure 3.

Each of the fittings or cylindrical members 48 is adapted to telescope with a tube or member 51. Extending into the upper portion of each tube 51 is a rod or journal pin 52. The upper portion of each rod 52 extends into the lower end of a second tube 54 as shown in Figure 6, the upper end of the second tube being preferably closed by means of a headed fitting or member 55. The back panel 39 is secured to these elements in the following manner. The screws 56 and 57 connect the panel 39 with the tube 51, the screws 57 also passing into threaded openings formed in the journal pin or rod 52. Each tube 54 is secured to the back panel by means of screws 58 and 59, the screws 58 passing into the threaded openings in the fittings 55 which serve to hold the latter in the tubes 54, the screws 59 passing through threaded openings in the upper portion of the rods 52. In this manner the screws 57 and 59 serve to secure each of the tubes 51 and 54 to the rods 52 as well as to the back panel 39.

The chair of my invention is provided with side arms 60 and 61 which are arranged for movement relative to the seat and seat back and to be swung to a position out-of-use. Journally supported upon the rods 52 are T-shaped members 63 which are formed with projecting tenons 65 which extend into the rear extremities of the tubular arms 60 and 61 and are of a dimension to be pressed or otherwise secured in the arms.

Means are provided for removably connecting the arms to the seat portion as particularly shown in Figures 6 and 8. Fixed in the forward end portions of each of tubular arms 60 and 61 are transversely extending pins 67, each pin extending through the eye of an eye bolt 68, each bolt being threaded to accommodate a wing nut 69. As illustrated particularly in Figures 7 and 8, the seat portion is formed with semi-cylindrical recesses 70, each of which is adapted to accommodate the extremity of a tubular side arm. Also formed in the skirt portion of the seat are slots 72 in communication with the semi-cylindrical recesses 70 to accommodate the eye bolts 68. As particularly shown in Figure 8 the interior side walls of the seat skirt portion 21 are formed with bosses 73, each having a face or surface arranged at an angle so that when the wing nuts 69 cooperating with eye bolts 68 are drawn up, the angular position of each eye bolt 68 is such as to exert a downwardly and inwardly directed force for obtaining a secure connection between each of the arms and the seat. The forward extremities of the arms may be disconnected from the seat by manipulation of the wing nuts 69 out of engagement with the bosses 73 after which the eye bolts 68 may be swung outwardly

to effect a release of the arms. The arms may be then swung about the axes of the pins 52 and rearwardly of the back panel 39 for collapsing purposes as hereinafter explained.

The chair is also provided with a feeding tray 17 which is supported centrally of the seat 10 and is made readily removable. As shown in Figures 1 and 11, a bolt 76 similar in construction to the bolts 28 projects through an opening in the forward skirt of the seat 10. A tubular support 77 for the tray is provided with an open ended slot 78 at its lower end which fits over the bolt 76 as shown in Figure 11. A clamping member 79 similar in configuration to the clamping members 73, cooperates with a wing nut 80 to secure the tray supporting tube 77 in a position-of-use. Mounted upon the upper end of the support or tube 77 is a fitting 82 having a boss portion 83 which is bored to snugly receive the upper end of the tube 77, the tube being snugly pressed into the bore in the boss 83 to retain the parts in fixed relation.

The fitting 82 is formed with spaced parallel portions 85 having upwardly and outwardly flared surfaces 96 and flat upper surfaces 87, the surfaces 86 and 87 forming ways for supporting the tray 17. The lower surface of the tray 17 is formed with depending projections 89 which straddle or embrace the angular walls 86 formed on the fitting 82, the members 85 and projections 89 serving to guide the tray and provide for a fore and aft adjustment thereof. Extending transversely of the fitting is a pin 90 and formed beneath the central portion of the pin is a recess 91 adapted to accommodate a latching pawl or tray retaining means 92 as particularly shown in Figure 11. The pawl 92 has a portion 93 adapted to lie in the path of a plurality of teeth 94 of a rack formation formed upon the lower surface of the tray 17. The latching pawl 92 is normally urged into engagement with the teeth 94 under the influence of a coil spring 95 fitting in a depression 96 formed in the fitting. The pawl 92 is formed with a depending trigger portion 97 for manipulating the pawl to release the same from engagement with the teeth 94. As particularly shown in Figure 11 the teeth 94 are preferably formed of a ratchet-type configuration so that the tray 17 may be moved in a direction toward the chair without manipulating the pawl 92. By this arrangement an infant or occupant of the chair cannot move the tray forwardly of the chair by exerting force on the tray without releasing the pawl, hence providing additional safety for the infant occupying the chair. By manipulating the trigger portion 97 of the latching pawl 92, the latter may be pivoted around the axis of the pin 90 in a counter-clockwise direction as viewed in Figure 11 to effect a release of the pawl projection 93 from the teeth 94 so as to enable the tray 17 to be moved forwardly with respect to the chair. The tray may be completely disconnected from the supporting fitting 82 by forward movement away from the chair. If it is desired to completely remove the tray and its supporting tube 77 from the chair it is only necessary to manipulate the wing nut 80 releasing the clamp 79 from engagement with the tube 77, after which the tube may be elevated out-of-engagement with the bolt 76.

It may, sometimes, be desirable to remove the tray 17 from the fitting 82 and place the same upon a supporting table or other surface. In order to maintain the tray in a stable position upon such surface there is provided a plurality

of projections or legs 100 integrally cast or formed with the tray structure and which project slightly below the lower terminae of projections 89 so that the projections will not engage a uniplanar support upon which the tray may be placed.

An adjustable foot rest means 16 is provided to facilitate the comfort of an infant. The seat 10 is formed with pairs of projections or lugs 102, 103, each pair being provided with a pin 105 passing through aligned openings formed in each pair of projections. Disposed between each pair of projections or lugs is a member 106 formed at its lower extremity with an L-shaped configuration to accommodate plates 107 and 108 providing supports for the infant's feet. Each of the members 106 are of identical construction and are configurated intermediate their ends with a plurality of recesses or depressions 109, the members being arranged to be selectively moved into cooperative relation with the pins 105 for adjusting the foot rest to several different positions. Each of the members 106 is formed with an arcuate or curved upper surface 110, the curvature of which and its relation to the axis of pin 105 and to the recesses 109 being of such that when the members 106 are shifted to move different pairs of recesses 109 into engagement with pins 105, a different portion of the arcuate surface 110 is caused to engage the lower surface of the seat portion 10. The lower surface of the seat cooperates with the arcuate surfaces 110 as a limiting means therefor to determine the several positions of the foot rest depending upon the selected pairs of recesses 109 in engagement with the pins 105. As shown in Figures 3 and 4, there are four recesses in each of the members 106 which provides for four independent positions for the foot rest 16. The forward skirt portion of the seat 10 is provided with slots 112 arranged to accommodate members 106 when the latter are moved to an upper-most position as shown in Figure 4. It is to be understood that other positions of the foot rest may be had or more or less positions of adjustment may be obtained by changing the number or dimension of the recesses 109 in members 106.

The chair of my invention is especially constructed and arranged to be folded or collapsed to occupy a small space so that the same may be readily transported or rendered portable. When it is desirable to prepare the chair construction for purposes of portability, each of the legs 23 and 24 is disengaged from the seat portion simply by partially backing off the wing nuts 36 after which the legs may be withdrawn from engagement with the bolts 28 and the fittings 30. The tray 17 and tray supporting tube 77 may be removed by partially backing off the wing nut 80 and elevating the tube 77 out of engagement with the bolt 76, clamping member 79 and fitting 81. The side arms 60 and 61 are then disengaged from the recesses 70 by partially backing off the nuts 69 and swinging the eye bolts 68 out of engagement with the bosses 73. After this disengagement is effected, the side arms 60 and 61 may be swung rearwardly around the axes of the pins or journals 52 and rearwardly of the seat back panel 39. The seat back panel 39 may then be swung into parallelism with the seat 10, the seat back panel and side arm construction being shown in folded position in Figure 7. By this means, it will be observed that the construction in disassembly may be reduced to small dimension so as to occupy a comparatively small space during transportation of the chair. Thus I have pro-

vided a chair which may be readily folded and disassembled and carried in an automotive vehicle, and which may be readily and quickly reassembled to a position-of-use. Furthermore the major constituents of the chair construction may be fabricated of metal and connected together by the means illustrated and described and provide when assembled a very sturdy and rigid chair, not liable to be broken or damaged through severe use. The extremities of the threaded portions of bolts 28 and 76 are preferably distorted after the wing nuts and clamps are placed thereon in order to prevent inadvertent removal of the wing nuts. It should be further noted that the center support for the tray and the tray per se provides a means for maintaining the infant in the chair especially as the tray may be freely moved in a direction toward the infant and is readily and automatically locked in such position through engagement of the pawl 92 with the ratchet teeth 94. The tray may be quickly removed by manipulating the trigger portion of the pawl 92 and the tray withdrawn for purposes of cleaning the tray or facilitating the removal of the chair occupant. Furthermore the tray and its support may be completely removed to render the infant's or children's chair adaptable for many other purposes.

It is apparent that, within the scope of the invention, modifications and different arrangements may be made other than is herein disclosed, and the present disclosure is illustrative merely, the invention comprehending all variations thereof.

What I claim is:

1. In a chair having legs, arms, back, and a seat portion, a readily removable tray with depending projections supported by means disposed centrally of the seat portion, said means consisting of a rigid tubular support having its lower portion bolted to said seat portion, said support having a fitting rigidly secured at the top thereof, said fitting formed with horizontally spaced parallel portions having upwardly and outwardly flared surfaces and flat upper surfaces forming ways for supporting the tray, and means for adjusting the tray horizontally with respect to said back and said rigid tray supporting means while said projections embrace said outwardly flared surfaces.

2. In a child's high chair having legs, a back portion, arms and a seat portion, a readily removable tray supported by means disposed forwardly and centrally of the seat portion, said support rigidly connected to the forward portion of said seat portion, said tray relatively movable horizontally with respect to said support, pawl and ratchet means associated with said tray and said support for normally allowing free movement of said tray in a direction toward said back portion and restraining movement of said tray in a direction towards said support and away from said back.

3. In a chair having a plurality of supporting legs, a back portion, a pair of arms hingedly associated with the back portion, and seat portion, a readily removable tray with a plurality of legs formed therewith, said tray supported by a tubular support disposed and rigidly secured forwardly and centrally of the seat portion, said support having mounted upon its upper end a fitting having horizontally arranged angular walls, said tray having a guide way formed in the underside thereof to embrace said angular walls of said fitting, said tray relatively movable hori-

zontally with respect to said fitting and its support, and means for allowing free movement in a direction toward said back portion and restraining movement of the tray horizontally in a forward direction away from said back portion and with respect to said support and said fitting.

4. In a chair having legs, arms, back, and a seat portion, a readily removable tray with depending projections supported by means disposed and rigidly secured forwardly and centrally of the seat portion, said means consisting of a rigid tubular support having a fitting rigidly secured to the top portion thereof, said fitting formed with horizontally spaced parallel portions having upwardly and outwardly flared surfaces and flat upper surfaces forming ways for supporting said tray, means for adjusting said tray horizontally with respect to the tubular tray supporting means, and pawl type means for restraining movement of the tray with respect to the rigid tray supporting means while said projections embrace said outwardly flared surfaces.

5. In a chair having legs, back, arms and a seat portion, a readily removable tray with depending portion supported by tubular means attached to the seat and disposed forwardly and centrally of the seat portion, said means consisting of a rigid tubular support having a fitting rigidly secured to the top portion thereof, said fitting formed with horizontally spaced parallel portions having upwardly and outwardly flared surfaces and flat upper surfaces forming ways for supporting said tray, means for adjusting the tray horizontally with respect to the tray supporting means, said adjusting means including a plurality of teeth formed on said tray, and pawl means adapted for cooperation with said teeth for restraining relative movement of the tray with respect to said rigid tray supporting means while said projections embrace said outwardly flared surfaces.

6. The combination, with a child's high chair having a back and a seat, of a readily removable tray and a stationary vertical support for said tray secured to the forward and central portion of said seat, of a horizontal guide-way associated with the under side of the tray, a horizontal guide associated with said support, said tray and guide-way relatively movable horizontally with respect to said horizontal guide and its vertical support, and a spring actuated pawl type means for restraining movement of the tray horizontally away from said back and with respect to said support.

7. The combination, with a child's high chair having a back and a seat, a readily removable tray and a support for said tray, said support being stationary with respect to said seat, said support being rigidly secured to the forward portion of said chair seat, said tray having means on the under side thereof to cooperate with stationary horizontal means arranged upon the upper end of said support whereby said tray is relatively movable horizontally with respect to said means upon the upper end of said support, said tray having a plurality of teeth formed on the under side thereof, pawl and ratchet means associated with said tray support for normally restraining movement of said tray in a horizontal direction with respect to said support, and forwardly away from the back of said chair, said tray positioned between said arms and free therefrom.

JOHN E. HUBER.
